Attorney.

UNITED STATES PATENT OFFICE.

EDWARD G. ROWLEY, OF BELLEVILLE, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed October 7, 1925. Serial No. 61,047.

This invention relates to a revoluble platen for typewriters, and its object is to provide a simple and inexpensive construction which will answer the requirements of typewriting and also be very quiet in operation.

In securing these ends in a preferred manner, an ordinary wooden platen core may be converted into a spool by cutting it away circumferentially for nearly its entire length, leaving a core provided with a head at each end, for convenience in attaching the usual platen ends. The core between these heads is left cylindrical.

Upon the cylinder of such a spool is wound fine threads or strands of cotton to form a quiet and locally yielding backing which is not bodily elastic. Many strands may be wound simultaneously. This result can best be obtained by employing the same multi-strand cord which is used in making cord tires for automobiles, preferably Sea Island cotton cord. This automobile cord consists of numerous strands or

fine cords, which are twisted into a single large cord or cable and so used in the tires. In making a platen, the large cord or cable can be untwisted so as to flatten it into the shape of a multiple-ply tape or ribbon of oval cross-section, which is wound upon said wooden core. In order that the windings may be made smooth and tight, it is proposed to secure one end of the tape to the small diameter of the spool at one end thereof by overlapping the first turn upon the end of the tape and then by rotating the platen to wind the tape tightly therearound in a pitch equal to the width of the tape, thus providing a first layer or primary

winding. The second layer may be in reality a continuation of the first, since the tape may be long enough for a double winding. Upon reaching the end of the platen, the tape is wound backwardly over the first layer.

Then the cord is secured to the spool and the surplus at the end is cut off, and the wound core will be of substantially uniform diameter, the winding being practically smooth and tight, thereby providing a backing for the platen jacket or casing; and the backing will be flexible enough to deaden the noise of the type-blows and also suitably back the work when manifolding. Over this assembled core there is forced an ordinary cloth-lined rubber shell, such as usual-

ly serves for the printing surface or jacket of the platen.

It is found that a platen made in this way is excellent for clearness of printing, for manifolding, and for all typewriter purposes, while the tight superposed layers of cord windings give the further effect of quietness to the type-blows.

Other features and advantages will hereinafter appear.

In the accompanying drawings, Figure 1 is a side view of the platen, showing the first layer of cord partly wound around the small diameter of the wooden core.

Figure 2 is a side view of the platen, showing the finished core ready to be inserted into the rubber shell.

Figure 3 is a fragmentary side view of the platen, showing the core partly inserted into the shell.

Figure 4 is a cross-sectional view, showing the assembled platen.

Figure 5 is a cross-sectional view through the line 5—5 of Figure 4.

Figures 6 and 7 are cross-sectional views of the cord, showing the cord, respectively, in its twisted and untwisted form.

A standard Underwood platen having a wooden core may be advantageously utilized for the purpose of this invention. Said core may be undercut forming substantially a spool having a small diameter 10 and unturned portions 11 at the ends thereof for the purpose of receiving screws 12, securing end metal caps 13 and 14 to the platen. The cap 13 has ratchet teeth cut on its periphery for the purpose of line-spacing the platen, while the cap 14 is provided with a screw 15 for securing the platen to a platen-axle 16.

In order to absorb the shock of the type-blows and thus eliminate the noise ensuing therefrom, there is provided a filler in the spool which substantially repletes the turned-down portion, so that, when the filler is in place, a core of a uniform diameter will be provided for receiving a rubber shell 17.

The filler used in this invention to raise the small diameter 10 to the diameter of the unturned portions 11 consists of Sea Island cotton cord, the same as is used for making automobile tires. The cord, which may be bought in the market, has a plurality of thin twisted strands, and one of the

varieties preferably used in this invention is known as 36 ply, indicating that it has thirty-six strands, the cord being twisted to about one-eighth of an inch in diameter.

5 Preparatory to winding the cord around the core of the platen, the same is untwisted so that the strands will be substantially straight and parallel, and then the cord resembles a tape 18, shown in cross-section in 10 Figure 7, and is about five-sixteenths of an inch wide. The end 19 of said tape 18 is secured to the wooden core by overlapping the first turn over the end of the cord in a manner as shown in Figure 1, and then the 15 platen is rotated to wind the cord therearound in a pitch equal to the width of the tape. The first ply being of a uniform thickness of about three-sixty-fourths of an inch is wound upon the core, whereupon the last 20 turn at the opposite end of the platen is made to overlap the previous turn, as shown at 20 in Figure 2. A second ply of cord is wound over the first one, the pitch being equal to the pitch of the first ply, and upon 25 completion of the second ply the end of the cord is nailed by means of a staple 21, or is otherwise secured to the spool against displacement.

30 Since each of the windings is about three-sixty-fourths of an inch thick, it is obvious that the two windings will represent a total thickness of three-thirty-seCONDS of an inch, which is ample to deaden the noise arising from the type-blows, while at the same time 35 providing a strong enough backing to resist the hardest blows when manifolding. The depth of the groove turned on the platen should, of course, be slightly less than the total thickness of the cord layers, since the 40 cotton is somewhat flexible and is compressed when the rubber shell is pressed thereon, as shown in Figure 3.

The core of the platen, after the cord has 45 been wound thereon, is shown in Figure 2 in which an additional staple 22 is shown to hold the cord against displacement. Upon said core there is provided the rubber shell 17 of standard hardness, the same as is used in the Underwood platens. Said shells are 50 usually cloth-lined and provide a simple and efficient means for securing the shell to the core. One of the methods commonly used to secure the shell to the core is to glue it thereto, although it could easily be nailed or otherwise secured against displacement.

55 Variations may be resorted to within the scope of the invention, and portions of the improvements may be used without others.

Having thus described my invention, I 60 claim:

1. A platen for a typewriting machine including a cylindrical core having a reduced cylindrical diameter extending the full length of the platen except for full-size head portions at the ends thereof, means for se-

curing said core to a platen-axle, tight windings of cord around the turned-down diameter of said core, said diameter between said heads being increased solely by said tight windings to substantially the full diameter 70 of the core so as to form a core having a uniform diameter, and a printing-surface shell closely fitting over said core.

2. A platen for a typewriting machine including a cylindrical core having a turned-down cylindrical diameter extending substantially the full length of the platen except for unturned portions at the ends thereof, means for securing said core to a platen-axle, a filler for raising the turned-down 75 diameter of the core to substantially the diameter of the unturned diameter thereof, said filler consisting of a multiple-strand flattened cord having one end secured to the turned-down diameter of the core at one end 80 thereof, and wound therearound, side by side, at a pitch equal to the width of the cord, so as to provide a uniform layer of cord, and then rewound over the first layer to provide a second layer parallel to the first, the total 85 thickness of the two layers being equal to the depth of the cut in the core, so that the outside diameter of the turned-down portion of the core will be substantially equal to the unturned diameter, and a rubber shell closely 90 fitting over said core, the inside diameter thereof being slightly smaller than the outside diameter of the core.

3. A platen for a typewriting machine having a wooden core, a rubber shell encasing said core, and layers of cotton-cord wound tightly around said core and serving as a backing for the rubber shell to deaden the noise arising from type-blows upon the rubber shell, said tight windings of cord 100 forming the entire backing between said core and said shell.

4. A platen for a typewriting machine having a wooden core, a rubber shell encasing said core, a double layer of cotton-cord consisting solely of tight windings running around said core and serving as a backing for the rubber shell to deaden the noise arising from type-blows upon the rubber shell, heads at the ends of said core, and means for securing the ends of the cord to said wooden 110 core.

5. A platen for a typewriting machine including, in combination, a hollow core, means for securing said core to a platen-axle, a tight cord winding over said core for deadening type-blows, and a hard printing-surface shell encircling and closely fitting over said cord winding, said tight winding filling the entire space between said core and said 120 shell.

6. A platen for a typewriting machine including, in combination, a hollow core, means for securing said core to a platen-axle, tight windings of cord upon said core 125

for deadening type-blows, a hard rubber shell closely fitting over said cord winding, and heads at the ends of said core equal in diameter to the outer diameter of the cord winding, presenting a uniform diameter core upon which the hard rubber shell is secured.

7. A platen for a typewriting machine including, in combination, a hollow core, means for securing said core to a platen-
10 axle, a rubber shell of standard hardness, and means between the shell and the core for deadening the noise arising from type-blows upon the rubber shell, said last-mentioned
15 means including a layer of multiple-strand Sea Island cotton-cord tightly wound upon said core, and a second layer tightly wound upon the first, the ends of said cord being secured to the shell in a manner to prevent
20 its displacement.

8. A platen for a typewriting machine including, in combination, a hollow core, means for securing said core to a platen-
25 axle, a rubber shell of standard hardness, and means between the shell and the core for deadening the noise arising from type-
blows upon the rubber shell, said last-mentioned means including a layer of multiple-
30 strand Sea Island cotton-cord tightly wound upon said core, and a second layer tightly wound upon the first, the ends of said cord being secured to the shell in a manner to prevent its displacement, said core being provided with heads at the ends thereof, the
35 diameter of said heads being equal to the outer diameter of the cotton layers, so as to present a core of uniform diameter to be inserted and secured to the rubber shell.

9. A platen for a typewriting machine including a wooden core, a cotton-cord covering tightly wound around said core, means for securing the cord to said core, the cord being wound in a manner to present two oppositely-slanting cross-wound layers, each
45 layer being of a uniform thickness, a hard

rubber shell over said cotton-covering, and means for concealing the cord at the ends of the platen.

10. A platen for a typewriting machine including a wooden core, a cotton-cord cov-
50 ering tightly wound around said core, means for securing the cord to said core, the cord being wound in a manner to present two oppo-
55 sitely-slanting cross-wound layers, each layer being of a uniform thickness, a hard rubber shell over said cotton-covering, and means for concealing the cord at the ends of the platen, said last-mentioned means including enlarged heads at the ends of said core and forming an integral part thereof, the diameter of said heads being equal to the inside diameter of the shell.

11. A platen for a typewriting machine including a wooden core, a cord wound therearound, said cord being rigidly at-
60 tached at one end of said core and being slantingly wound around said core, forming a layer of uniform thickness, a second layer of cord, the cord being wound in an oppo-
65 site slanting direction to the first layer, and a hard rubber shell closely fitting over the cord windings.

12. A platen for a typewriting machine including a wooden core, a covering for said core consisting solely of a tightly-wound 70 sound-deadening cord, and a rubber layer tightly fitting over said cord-covering.

13. A platen for a typewriting machine including a wooden core, a cord tightly wound around said core, means for securing 80 the cord to said core, the cord being wound in a manner to present two oppositely-slanting cross-wound layers, each layer being of a uniform thickness, a hard rubber shell over said cord, said tight windings filling 85 the entire space between said core and said shell, and heads at the ends of said core, the diameter of said heads being equal to the inside diameter of the shell.
